ORTHODONTIC ANCHORAGE

Russell E. Irish, Pittsburgh, Pa.

Application October 31, 1932, Serial No. 640,388

5 Claims. (Cl. 32—14)

This invention relates to an orthodontic anchorage of the type in which a wire is connected with a tooth by the insertion of the wire, or a plug carried thereby, into a socket mounted on a band carried by the tooth.

It is of primary importance that the engagement between the plug carried by the wire, and the socket or sheath mounted on the band be such as to minimize the possibility of accidental withdrawal of the plug. Various forms of inter-engagement between the plug and the sheath have been proposed to effect this general object. I have discovered that a firm engagement between plug and sheath is best obtained by a complexity of structure which increases the friction-producing area of contact between the parts, and which gives an engagement resisting loosening movement of the plug in the socket.

The area within which this desirable complexity must be comprised is very restricted, because of the use to which the apparatus is put, and for this reason, so far as I am aware, complexity of cross-sectional contour of plug and sheath has not heretofore been successfully attempted.

I have, however, devised a specialized plug and sheath contour which, when carefully prepared, provides great complexity of cross-sectional contour and adequate strength within a minimized cross-sectional area.

A further, and specific, object of my invention is obtained by making lengths of finished shafting and lengths of tube, which are both of uniform cross-sectional contour and area through their length, so that they may be prepared for use merely by cutting them into pieces of suitable length. Plugs and sockets of tapered form, or which are otherwise complicated longitudinally, rather than transversely of their axes, present prohibitive difficulties in manufacture.

In the accompanying drawing Figure I is an elevational view of a tooth and is generally illustrative of the mode of use of my orthodontic anchorage; Figure II is an elevation taken at the leaving end, showing a die arranged for the drawing of both the tubing and the shafting constituting the anchorage of my invention; Figure III is a cross-sectional view through the die on the line III—III of Figure II; Figure IV is a cross-sectional view through the die on the line IV—IV of Figure II; Figure V is an isometric view of the strip used in making the tubing or sheath, on a greatly enlarged scale, showing the strip prior to its formation into a tube; Figure VI is an isometric view of the tube as formed from the strip shown in Figure V, on the same

scale as Figure V; Figure VII is a perspective view of the shafting which fits the tubing of Figure VI; and Figure VIII is an elevation taken at right angles to the plane of Figure I, showing a tooth, having thereon a band and a complete plug and sheath assembly provided by cutting and fitting together short pieces of the tubing and shafting.

Referring to Figure I of the drawing, reference numeral 1 designates a molar to which a band 2 is applied. An arch wire 3 is to be connected with the band 2 in such manner that it may be readily removed for adjustment during the long-continued process of tooth straightening. Attached to the band 2 is a sheath 4 which receives a plug, soldered, or welded, terminally to the arch wire 3. It may be noted initially that the band 2 lies upon, or closely adjacent, the soft gingival tissue 5 surrounding the tooth 1, and that the sheath 4 also rests upon the soft tissue. As explained, it is practically prohibitive in quantity manufacture to make either the sheath 4 or the plug of matching complex cross-sectional contour if plug members and sheath members be made individually. For this reason I have so designed the sheath and plug that they may be drawn in extended lengths, for subsequent subdivision into pieces of the proper size for use.

In providing these lengths of tubing and of shafting, I use a die 6, having therein drawing apertures for the tubing material 7, 7a, 7b, 7c, 7d, and having drawing apertures for the shafting 8, 8a, 8b, 8c, 8d, and 8e. In drawing of the tubing material, I may take a flat, or roughly formed, strip of metal of suitable composition for the ultimate purpose, and, by drawing it successively through the apertures from 7 to 7d, obtain an elongate, thin strip 9 of worked metal, having thereon marginal upturned flanges 10 and a longitudinally-extending rib 11, disposed centrally of the strip. Figure V of the drawing, showing the finished strip on a greatly enlarged scale, is provided with dimension lines for the purpose of illustrating the fineness of the sizing involved, and not on the assumption that the exact dimensions shown are necessary to success. Thus the dimension lines A represent .0145 inch, the dimension lines B, .0856 inch, the dimension lines C, .018 inch, and the dimension line D, .028 inch.

In die 6 a length of wire, which may initially be round, of a suitable metallic alloy is drawn first through the drawing aperture 8, and successively through the other drawing apertures

from 8a to 8e. When thus drawn, the result is a length of shafting 12, conforming in general cross-sectional contour to the letter H, but with its two legs 12a converging to one side of the crossbar 12b and diverging on the other side of the crossbar. This shafting also is worked down by elongation to the desired size and contour, and when suitable alloy known in the art is employed, the working does not impair the qualities of the metal constituting the shaft, or that constituting the tubing.

The tubing 13, which is to provide sheaths, or sockets, 4, receiving plugs cut from shafting 12, is formed by passing the finished strip 9 through suitable forming dies, which form it into a tube. In the tube structure, as shown in Figure V of the drawing, the longitudinally and centrally disposed rib 11 forms a longitudinal rib 4a within the interior of the tube, and the outer faces of the marginal flange or ribs 10 are brought into abutting relation, so that they also form an opposed longitudinally-extending rib 4b in the interior of the tubing. It will be noted that both the rib 4a and the rib 4b have sides inclined inwardly of the tube. In forming the tube it is constricted toward the wall opposite that at which its edges are brought into abutment. This constriction, which gives an interior contour matching the cross-sectional contour of the shafting, and increasing the interlocking effect between the shafting and the tubing, also permits the corners of the tubing to be smoothly curved, and prevents irregularities in the wall thickness of the tubing. As shown, the side walls of the tubing have an inclination of approximately sixteen degrees.

In preparing the anchorage for use, a length of the tubing is cut off, to provide a socket or sheath member 4, and is attached as by soldering, or welding, to the band 2, with its more extended face lying against the band. A plug 14 of suitable length is cut from the shafting 12, and the arch wire 13 is attached as by soldering or welding to the upper end of this plug, prior to insertion of the plug in the socket or sheath 4.

The lower end of the socket or sheath is specially prepared for use by cutting it away angularly, so that an edge 15 is provided at the wide face of the socket which is attached to the band 2. The edge 15 may enter the space which lies normally between the tooth structure and the soft tissue, with the angular, or slightly curved, lower edge of the socket resting on the tissue without penetration. This exterior contouring of the sheath is of value in preventing irritation of the soft tissue.

It should be understood that the relatively great surface engagement between the plug and sheath frictionally engages the plug in the sheath in a manner to prevent accidental displacement, or improper withdrawal. The interlocking of the plug and sheath prevents loosening movement of the plug in the sheath in any direction. I believe that the cross-sectional contouring of parts which I provide gives the greatest possible complexity of contour, while making all portions of the structure of dimensions as great as is possible in apparatus of such minute overall cross-sectional area. It is, further, a contour, which, as explained above, permits the forming of the sheath material in lengths of tubing, and the formation of the plug material in lengths of shafting for subsequent subdivision.

Although the plug is of complex cross-section

and the sheath or socket conforms interiorly to such contour, the exterior of the sheath or socket is smooth and rounded. It therefore does not tend to irritate the tongue, or other tissue, in contact with which it may come. It may be noted further that the interlocking complexity of the sheath or socket and the plug is obtained by an interior deformation of the socket wall, without any insetting into the body of the socket wall, which would require either the individual manufacture of sockets or an undesirable regional thinning of the socket wall.

An incidental advantage attendant upon the complex contour of the plug is that it may be firmly grasped for manipulation by tweezers or fine pliers.

An incidental advantage of the formation of the socket is that a slightly oversize socket may be tightened on a shaft by light blows or pressure. This is due to the positioning of the seam in the tubing, and the presence of the abutting ribs which provide a surface contact of the seam.

I claim as my invention:

1. In an orthodontic anchorage, a socket member comprising a base wall for attachment to a tooth-embracing band and a smooth unbroken outer wall extending from one side to the other side of the base wall and defining therewith an internal socket having an open end, two of the opposite walls of said socket member having opposing inset longitudinal ribs spaced apart and dividing the socket into spaced chambers with a connecting passageway between them, and a plug member of a size to pass into the open end of the socket, said plug member having spaced longitudinal portions and a reduced neck portion connecting the same, said portions fitting snugly in the chambers and passageway respectively and engaging the walls thereof with sufficient frictional engagement to hold the plug member against normal accidental displacement.

2. In an orthodontic anchorage, a socket member comprising a base wall for attachment to a tooth-embracing band, an outer wall of less width than the base wall and side walls that transversely converge from the base to the outer wall, said walls being integral, and the outer and side walls being smooth and unbroken and with rounded edges at their junctions, said walls defining an internal open ended socket, the said base and outer walls having opposing inset longitudinal ribs spaced apart and dividing said socket into outer chambers that are transversely tapered with a connecting passageway between them that extends between the ribs, and a plug member of a size to pass into the open end of the socket, said plug member having spaced longitudinal portions and a reduced neck portion connecting the same, said portions corresponding in transverse configuration to the configuration of the socket and fitting snugly in the chambers and passageway respectively and engaging the walls thereof with sufficient frictional engagement to hold the plug member against normal accidental displacement.

3. In an orthodontic anchorage, a socket member formed from a strip having a central and marginal longitudinally disposed ribs, said strip having its free edges in juxtaposition to form an open ended socket, the side margins of the strip constituting a seamed base wall adapted to be attached to a tooth-embracing band, said marginal ribs being inset into the socket in juxtaposition to each other to form in effect a single rib, and the central rib being inset into the

socket in opposition to the marginal ribs and spaced therefrom, thereby dividing the socket into outer chambers and a passageway connecting the same between the ribs, and a plug member that 5 enters the open end of the socket and has a cross sectional contour substantially corresponding in size and shape to the socket and having its various faces frictionally engaging the corresponding faces of the socket walls to be thereby maintained in the 10 socket, the outer face of the socket member being smooth and unbroken and the plug member having an exposed end for attachment to an arch wire.

4. In an orthodontic anchorage, a socket member formed from a strip having a central and marginal longitudinally disposed ribs, said strip having its free edges in juxtaposition to form an open ended socket, the side margins of the strip constituting a seamed base wall adapted to be 15 attached to a tooth-embracing band, said marginal ribs being inset into the socket in juxtaposition to each other to form in effect a single rib, and the central rib being inset into the socket in opposition to the marginal ribs and spaced 20 therefrom, thereby dividing the socket into outer chambers and a passageway connecting the same between the ribs, the opposing side walls of 25 said socket member springing from the base walls being outwardly convergent and the inner faces of the socket chamber being correspondingly convergent, and a plug member that enters the open

end of the socket and has a cross sectional contour substantially corresponding in size and shape to the socket and having its various faces frictionally engaging the corresponding faces of the socket walls to be thereby maintained in the 5 socket, the outer face of the socket member being smooth and unbroken and the plug member having an exposed end for attachment to an arch wire.

5. In an orthodontic anchorage, a socket member comprising a base wall for attachment to a tooth-embracing band and a smooth unbroken outer wall extending from one side to the other side of the base wall and defining therewith an internal socket having an open end, at least one 10 of the said walls having an inset longitudinal rib projecting from the plane of the wall into the bore of the socket to provide in the bore of the socket a constriction not represented on the outer surface of the socket, and a plug member of a 15 size to pass into the open end of the socket, said plug member having a longitudinal indentation matching the longitudinal rib in the bore of the socket and flanges formed by said indentation embracing the sides of said rib, said plug member 20 fitting snugly in the socket and engaging the walls of the socket and rib with sufficient frictional engagement to hold the plug against normal accidental displacement.
